UNITED STATES PATENT OFFICE

164,617

CUB SCOUT TROPHY

Howard Weitlauf, Seattle, Wash.

Application March 19, 1951, Serial No. 14,535

Term of patent 14 years

(Cl. D29—23)

To all whom it may concern:

Be it known that I, Howard Weitlauf, a citizen of the United States, residing at 3843 33rd Southwest, Seattle 6, State of Washington, have invented a new, original, and ornamental Design for a Cub Scout Trophy, of which the following is a specification, reference being had to the accompanying drawing, forming a part hereof.

Fig. 1 is a side elevational view of a cub scout trophy embodying my invention;

Fig. 2 is a plan view thereof; and

Fig. 3 is a front elevational view.

I claim:

The ornamental design for a cub scout trophy, as shown.

HOWARD WEITLAUF.
